UNITED STATES PATENT OFFICE.

EDWARD H. PARKE, OF FINDLAY, OHIO.

WHEELED TOY.

Application filed February 26, 1923. Serial No. 621,248.

To all whom it may concern:

Be it known that I, EDWARD H. PARKE, a citizen of the United States, residing at Findlay, in the county of Hancock and State of Ohio, have invented a new and useful Wheeled Toy, of which the following is a specification.

This invention relates to toys and more particularly to wheeled toys.

10 The object of the invention is to provide a simple, cheaply constructed toy for amusing small children.

15 With the foregoing and other objects in view which will appear as the description proceeds, the invention resides in the combination and arrangement of parts and in the details of construction hereinafter described and claimed, it being understood that changes in the precise embodiment of 20 the invention herein disclosed may be made within the scope of what is claimed without departing from the spirit of the invention.

In the accompanying drawings:

Figure 1 represents a longitudinal section 25 with parts broken out of the toy embodying this invention.

Fig. 2 is a top plan view thereof.

Fig. 3 is a rear elevation.

30 Fig. 4 is a detail sectional view showing the connection of the axle with one wall.

Fig. 5 is a face view of a central portion of one wheel with the slits shown therein which form the opening for the axle.

35 Fig. 6 is an end elevation showing a portion of one wheel and its connection with the axle.

Fig. 7 is a detail sectional view of the upper portion of the bell.

40 Fig. 8 is a similar view taken in a plane at right angles to Fig. 7.

The toy constituting this invention comprises a pair of wheels 1 and 2 fixedly connected with an axle 3 which is preferably made of wood and inserted through the central portions of the wheels and secured thereto by means presently to be described. 45 These wheels 1 and 2 are made in the form of sheet metal disks preferably of tin and are slit obliquely at their central portions as shown at 4 to provide triangular ears 5 which are bent outwardly at right angles to the body of the disk as shown clearly in Figs. 6 and 7 through which fastening elements 6 are designed to pass and enter the

axle 3 for securing the wheel to the axle as 55 is shown clearly in Figs. 4 and 6.

The wheels are preferably provided at their peripheries with outwardly extending lateral flanges 7 which form the treads of the wheels being made integral with the 60 disks greatly cheapen the construction of the wheels.

Extended through the axle 3 near the ends thereof are two pins 8 and 9 arranged in planes at right angles to each other and which project at their opposite ends some distance beyond the axle and are designed for a purpose presently to be described.

A bell supporting bracket 10 and a rod or tongue 11 are formed from a single piece 70 of heavy wire bent intermediate its ends to form the bracket 10 which is U-shaped and the legs of which are wound loosely around the axle as shown at 12, the axle turning freely within these looped portions. The members 13 and 14 of this wire are then extended forwardly parallel with each other to a point opposite the peripheries of the wheels when they converge as shown at 15 and 16 and are twisted together as shown at 17 to form a reinforcing push rod or handle. The free ends of the wire at the outer end of the handle are extended laterally in opposite directions and looped as shown at 18 and 19 to form a hand grip. This handle is designed for pushing or pulling the toy over the floor and may be of any desired length, being here shown bent at an obtuse angle at its junction with the members 15 and 16.

85 A sound producing device 20, here shown 90 in the form of a bell is suspended from the cross bar 10 of the bracket 10, being loosely mounted thereon by means of a wire 21 which is coiled around said cross bar, the central portion of said wire midway the 95 cross bar, being looped as shown at 22 and said bar extended at right angles to the body portion of the wire and threaded through apertures 24 in a block 23 carried by the upper portion of the bell and whereby said 100 bell is connected with a wire so that when the ends 26 and 27 of the wire which are shown extended inwardly at an angle are rocked, the bell will be swung and caused to ring, making a noise such as will amuse 105 small children. These deflected ends 26 and 27 of the wire 21 are positioned in the paths of the rods or pins 8 and 9 carried by the

axle 3 so that when the toy is drawn over the floor, the turning of the wheels turns also the axle causing these pins to alternately engage the ends or fingers 26 and 27 and swing the bell.

Various changes in the form, shape, proportion and other minor details of construction may be made without departing from the spirit or sacrificing any of the advantages of the claimed invention.

I claim:

1. A toy of the class described comprising a wheel supported structure including an axle having wheels fixed thereto, pins carried by said axle and extending in planes at right angles to each other and projecting at their opposite ends beyond the axle, a bracket mounted on the axle, a bell mounted to swing on said bracket, and fingers carried by the bell and located in the path of said pins whereby the turning of the axle will ring the bell.

2. A toy of the class described comprising an axle having wheels fixed thereto, pins extending radially from said axle, a U-shaped bracket having coiled portions in the legs thereof through which said axle extends, a bell, means loosely connecting the bell with the cross bar of said bracket to permit the bell to swing freely on said cross bar, said means including laterally extending fingers positioned in the path of the pins whereby turning of the axle will engage these fingers and ring the bell.

3. A toy of the class described comprising an axle having wheels fixed thereto, pins extending radially from said axle, a U-shaped bracket having coiled portions in the legs thereof through which said axle extends, a bell, means loosely connecting the bell with the cross bar of said bracket to permit the bell to swing freely on said cross bar, said means including laterally extending fingers positioned in the path of the pins whereby turning of the axle will engage these fingers and ring the bell, the legs of said bracket being extended in a plane at right angles to form a handle member connected with the coiled portion of said bracket.

4. In a toy of the class described, an axle having wheels fixed thereto, a combined bell supporting bracket and handle composed of a piece of heavy wire bent midway its ends to form a U-shaped bracket having coils in the legs thereof through which the axle loosely extends, the members of said wire extending at right angles from said coils and converging outwardly, said converging ends being twisted together and provided at their terminals with laterally extending loops to form a hand grip, a bell suspended to swing freely from said bracket and cooperating bell-ringing means carried by the bell and the axle operable on the turning of the axle to ring the bell.

5. In a toy of the class described, an axle having wheels fixed thereto, a combined bell supporting bracket and handle composed of a piece of heavy wire bent midway its ends to form a U-shaped bracket having coils in the legs thereof through which the axle loosely extends, the members of said wire extending at right angles from said coils and converging outwardly, said converging ends being twisted together and provided at their terminals with laterally extending loops to form a hand grip, a bell suspended to swing freely from said bracket, a wire wound loosely around the cross bars of said bracket, a bell depending from and fixedly connected with said wires, the ends of the wire being deflected inwardly and extended laterally to form fingers, and radial elements extending from said axle in position to engage said fingers to ring the bell on the turning of the axle.

6. A toy of the class described, comprising a wheel supported structure including a wooden axle and disk-like wheels having central openings provided with laterally extending ears, and means for fixedly connecting said ears to the ends of the axle.

In testimony that I claim the foregoing as my own, I have hereto affixed my signature in the presence of two witnesses.

EDWARD H. PARKE.

Witnesses:

GAIL BLACKFORD,
F. P. BLACKFORD.
